Application October 31, 1935, Serial No. 47,597

16 Claims. (Cl. 101—247)

My invention, which relates to printing presses, will be best understood from the following description when read in the light of the accompanying drawings of an embodiment of the invention, the scope of which latter will be more particularly pointed out in the appended claims.

In the drawings:—

Figure 1 is a side elevation of a machine constructed according to the invention;

10 Fig. 2 is a side elevation of the printing couple, with associated parts, shown at the right hand end of Fig. 1, parts being in section;

15 Fig. 3 is a side elevation according to Fig. 2 as viewed from the opposite side of the machine, parts being in section;

Fig. 4 is an end elevation of the printing couple, with associated parts, as viewed from the right of Fig. 1;

20 Fig. 5 is a section on the line 5—5 of Fig. 1 on an enlarged scale;

Fig. 6 is a plan, on an enlarged scale, of the strip guiding and tensioning means of Fig. 1;

Fig. 7 is a section on the line 7—7 of Fig. 6;

25 Fig. 8 is an enlarged fragment of the frame showing a detail of the bearing for the shaft of the print roll;

Fig. 9 is a section on the line 9—9 of Fig. 5, with parts omitted;

30 Fig. 10 is a section on the line 10—10 of Fig. 5, with parts omitted;

Fig. 11 is a section on the line 11—11 of Fig. 2, with parts omitted;

35 Fig. 12 is a section on the line 12—12 of Fig. 3, with parts omitted and parts moved to a different operative position;

Fig. 13 is a section on the line 13—13 of Fig. 5, with parts omitted;

Fig. 14 is a section on the line 14—14 of Fig. 2, with parts omitted;

40 Fig. 15 is an elevation, on an enlarged scale, of the clutch release mechanism of Fig. 1; and

Fig. 16 is an end elevation of the mechanism of Fig. 15.

Referring to the drawings, the press illustrated 45 comprises a pair of standards 1 at the upper ends of which on opposite sides are mounted the spaced, longitudinally extending channel-irons 3. Supported on these channel-irons above the standards are printing couples having the print 50 rolls 5 and presser rolls 7 for operating upon a narrow strip 9 of sheet material which is drawn from a reel 11, and, after being printed and dried, wound upon a reel 13.

As illustrated, the print rolls and presser rolls 55 are carried by frames comprising the side mem-

bers 15 and 17 (Figs. 4 and 5). As the construction of each frame and printing couple is similar only one will be described.

As shown, the print roll 5 is located between the side members of the frame and is carried by 5 a shaft 19. The bearings for this shaft comprise lower bearing blocks 21 inserted in the side members of the frame, and upper bearing blocks 23, the latter being hingedly connected to said side members at 25, as best illustrated in Figs. 2 and 8. 10 The upper half 23 of the bearing is shown as provided with a boss 27 formed with a bore 29 in which is reciprocally mounted a plunger 31, the latter having an enlarged head 33 fitting the bore and being formed with a tapered end 35 which is 15 received in a correspondingly shaped recess in the adjacent side member of the frame. A compression spring 37, positioned in the bore 29 and surrounding the plunger 31, acts on the head 33 normally to hold its tapered end 35 in this recess 20 to lock together the halves of the bearing. At its opposite end the plunger projects from the boss 27 and is provided with a head 39 which may be gripped to retract the plunger against the pressure of the spring and withdraw the tapered end 25 35 from its recess. This enables the upper half of the bearing to be swung into its dotted line position shown in Fig. 8, in which position it rests on the horizontal portion 41 of the frame.

The above described bearing construction 30 allows the print roll to be readily removed from the frame, and, when the upper half of the bearing is swung into its dotted line position, affords a preliminary rest for the print roll in removing it from or inserting it in the frame, because when 35 in its dotted line position the upper bearing half has its bearing surface facing upward, allowing the shaft 19 of the print roll to rest in it, as shown in dotted lines in Fig. 8.

As illustrated, for adjusting the print roll 5 40 longitudinally thereof between the guide members of the frame, a reduced end portion of the shaft 19 is provided with a pair of collars 43 and 45 (Fig. 4), the latter of which is formed integrally with a worm 47 forming part of the mechanism 45 hereinafter described for operating the doctor knife 48 (Figs. 5 and 13), sufficient space 49 (Fig. 4) being left between the bearing for the shaft and the worm to permit this adjustment. An arm 51 is pivotally mounted at its lower end on 50 a pin 53 (Figs. 3 and 4) supported in lugs 55 carried by the adjacent side member 15 of the frame. The upper end of this arm is bifurcated, as indicated at 57 (Fig. 3), the arms of the bifurcations carrying pins 59 which fit between the 55

collars 43 and 45. Extending transversely through the arm 51, in screw-threaded relation therewith, is a screw 61. This screw at its left hand end, as viewed in Fig. 4, bears against the outer face of a lug 63 carried by the side member 15 of the frame. The arm 51 is urged to the left, as viewed in Fig. 4, by a spring 65 attached at one end to the arm and at its opposite end to the side member 15 of the frame. This construction 10 provides, in an obvious manner, that by rotating the screw 61 by means of its knurled head 67, the shaft 19 and the print roll carried by it may be adjusted lengthwise.

The two printing couples are driven by a shaft 15 69 extending longitudinally of the bed of the machine and mounted in bearings 71 on the frames of the several printing couples. This shaft is provided with a belt pulley 73 (Fig. 2) about which passes a belt 75 driven by a motor 71. On the 20 shaft 69, at each printing couple, is splined a longitudinally shiftable worm 79 held in adjusted position lengthwise of the shaft by a housing 81 (Figs. 2 and 11). The ends 83 of this housing abut with the ends of the worm, a ball thrust 25 bearing 85 for taking up the thrust of the worm on the housing being interposed between one end of the worm and the adjacent end wall of the housing. The housing may be shifted longitudinally of the shaft, for adjusting the worm, by 30 means of a screw 87, which screw is in screw-threaded engagement with the downwardly projecting lug 89 formed integrally with the housing, the screw being rotatably supported in lugs 91 formed integrally with the adjacent side member 17 of the printing couple frame. For conveniently rotating the screw it is provided at its 35 end with a handle member 93.

Meshing with the worm 79 is a worm wheel 95, which operatively is formed integrally with a 40 spur gear 97 (Figs. 2 and 11) meshing with a spur gear 99 fixedly carried by the shaft 19 of the print roll. This construction provides, that when the worm is shifted longitudinally of the shaft, by rotation of the screw 87, the print roll 45 will be rotated so as to adjust it angularly relative to the shaft 69.

The presser roll 7 is carried by a shaft 101 which is mounted on the ends of arms 103 pivotally connected to the side members 15 and 17 of the frame at 105. As illustrated, these arms are connected by a bar 107 formed integrally therewith extending across and above the top of the frame. Also extending across the top of the frame below the bar 107 is a bar 109 integrally formed with the side members of the frame. The bar 107 is perforated, as indicated at 111 (Figs. 5 and 9), and through this perforation extends a vertical rod 113 which is of less diameter than the perforation and is rigidly secured at its lower end to the bar 109. This rod at its upper end is screw-threaded and carries a nut 115 serving as the upper abutment for a compression spring 117, the lower abutment for which is afforded by a collar 119 slidably mounted on the rod. Pivoted to this collar at 121 are the upper ends of links 123 which at their lower ends are pivoted at 125 to the upper ends of links 127, the latter at their lower ends being pivoted at 129 to spaced lugs 131 formed integrally with the upper side of the bar 103.

It will be observed, that by the construction just described, when the parts are in the position shown by the drawings, the spring 117 is effective to press the arm 103 downward to hold the 75 presser roll yieldingly in engagement with the

print roll, or yieldingly in engagement with the sheet which passes between the two rolls.

As shown, the right hand link 127, as viewed in Fig. 5, is extended upward to form an arm 133 to which is pivotally connected a bar 135, the bar 5 extending from the arm 133 associated with one printing couple to the corresponding arm associated with the other printing couple. The bar 135, as shown, is provided with convenient handle means 137 which may be gripped by the operator for reciprocating the bar. As shown (Figs. 2 and 5) the two links 127 are connected by a bar 139 having at opposite ends arms 141 integrally connected with the links. By moving the bar 135 to the left, as viewed in Fig. 2, the links 127 will 15 be swung about their pivots 129 which will move the collar 119 downward beyond the short limit of expansion of the spring 117 to render the spring inoperative to press the bar 107 carrying the presser roll downward. In fact, the construction described, it will be observed, forms a toggle comprising the links 123 and links 127, and moving the toggle beyond its dead center position, that is to say, the position in which the pivotal connections 121, 125, and 129 are in 20 alignment, the spring will automatically move the collar 119 downward to the limit of expansion of the spring. As will be clear from Fig. 2, the bar 139, which connects the two links 127, is positioned sufficiently far from the rod 113 to 25 enable the presser roll 7 to be moved upward sufficiently to permit the print roll to be removed from its bearings, that is to say, it is permitted to move upward a distance of at least about the radius of the print roll. As shown, the two links 30 123 are integrally connected by a bar 143 which carries a set screw 145 the end of which is adapted to contact with the rod 113. This set screw is 35 adjusted to cause its end to contact with the rod when the pivotal connections 121, 125, and 129 are moved to just past dead center position by 40 moving the bar 135 to the right as viewed in Fig. 2. This will cause the parts to be automatically held by the spring 117 in the position of parts shown by the drawings.

On the under side of each arm 103 presses a spring pressed plunger 147 (Figs. 2 and 3) mounted in a hollow boss 149 formed integrally with the side members of the housing. Upon release of the toggle above described, the spring 151, which acts on the plunger 147 and is of lesser strength than the stout spring 117, is effective to raise the presser roll 7 out of cooperation with the print roll 5.

For guiding the sheet, each printing couple has 45 associated with it a guide (best shown in Figs. 4, 9, and 14). This guide comprises a flat bar 153 having upwardly projecting end portions 155, which latter are slotted at 157 and secured to the presser roll supporting arms 103 by screws 60 159 passing through the slots so that the bar 155 may be adjusted vertically. The sheet rests 65 upon the upper surface of the bar 153. Slidably supported in the upwardly extending portions 155 of the guide is a rod 161, to which latter 70 may be adjustably secured members 163 which 75 loosely engage with the opposite edges of the sheet. These members 163 are recessed at 165 (Fig. 9) so as slidably to fit the bar 153. At their upper portions they are split, as indicated at 167, 70 and through the split portions pass screws 169 which serve to clamp the members to the rod in adjusted position longitudinally thereof. For moving the two members simultaneously longitudinally of the bar 153 to secure a fine adjust- 75

ment, the rod 161 at one end is screw-threaded into a nut 171 (Fig. 14) which is rotatably mounted in one of the upwardly extending members 155, this nut having a knurled head 173 so that it may be conveniently rotated.

The worm 47 for operating the doctor knife 48 meshes with a worm wheel 175 (Figs. 3, 4, and 10), which worm wheel is rotatably mounted on a pin 177 carried by the lug 63 on the side member 15 of the frame. The worm wheel is provided with a hub, which at its end is provided with an eccentric pin 179 on which is mounted a roller 181. As shown, the roller is fitted into a slot 183 formed in the arm 185 and extending longitudinally thereof, this arm 185 at its lower end being mounted for oscillation on the pin 53 hereinbefore referred to. At its upper end the arm 185 carries a projecting pin 187 which, as best illustrated in Fig. 5, fits between a pair of collars 189 on and fixed to a reciprocating shaft 191 which carries the doctor knife (Figs. 5 and 13). Rotation of the worm wheel 175, therefore, causes oscillation of the arm 185 about its pivot afforded by the pin 53, and this oscillation, through engagement of the pin 187 with the collars 189, reciprocates the shaft 191, and therefore reciprocates the doctor knife. Rotation of the shaft is urged by means of weights 193, which are carried at the ends of arms 195 projecting radially from the shaft. By securing the arms 195 in different adjusted positions radially of the shaft, by means of the set screws 197 screw-threaded in the ends of the shaft and bearing against the rods 195 which project through holes in the shaft, the pressure of the doctor knife on the print roll may be varied.

As shown, the shaft 191 is mounted on bearings 199 which are slidably mounted on guides 201 carried by the side members of the frame. Screws 203 screw-threaded into the frame, and having their inner ends swiveled to the bearings 199, are effective for adjusting the bearings, and hence the shaft 191 and doctor knife, toward or away from the print roll.

The reel 13, as shown, is rotated by a belt 205 driven from a pulley 207 adapted to be clutched to the shaft 69. As illustrated (Fig. 15) this clutch is of a common type having friction disks 209, the latter being situated between the pulley 207 and the end disks 211 and 213, the latter of which end disks is fixed to rotate with the shaft 69, while the former, and the friction disks and pulley as well, are rotatably mounted on the shaft. By pressing the disk 211 toward the disk 213, by means of the collar 215, slidably mounted on the shaft, and the interposed thrust bearing 217, the pulley 207 is caused to rotate with the shaft. When the collar 215 is moved to the left, as viewed in Fig. 15, the clutch thus formed will be thrown out, and the pulley will not rotate with the shaft.

As illustrated, for sliding the collar 215 along the shaft 69, the side member 17 of the frame of the left hand printing couple, as viewed in Fig. 1, is provided with a projecting bracket 219 (Fig. 15) carrying a laterally projecting pin 221 on which is pivotally mounted a bell crank lever having the arms 223 and 225, and also pivotally mounted thereon is an arm 227. As shown, the end portion of the arm 225 is slotted, as indicated at 229, and through this slot passes a screw 228 which rigidly attaches the arm 225 to the arm 227 so that the latter arm and the arm 223 in substance form a bell crank lever of adjustable angle. As illustrated in Fig. 16, the lower end of

the arm 223 is bifurcated, and is secured to the collar 215 by pivot pins 230. The bracket 219, as shown, has an upwardly extending member 231 which serves as the lower abutment for a compression spring 233, the upper abutment for which is afforded by a nut 235 screw-threaded on the end of a rod 237, the lower end of the rod being pivotally attached to the arm 227 at 239. By this construction the spring 233 forces the collar 215 to the right, as viewed in Fig. 15, so as to hold the pulley 207 clutched to the shaft 69, the clutch pressure being regulated by adjusting the nut 235 longitudinally of the rod 237. Conveniently this pressure is such as to allow the pulley 207 to slip under normal operation so as to maintain under tension the strip being printed and to compensate for the increasing diameter of the roll of strip on the reel.

As shown, pivoted at 241 to the side member 17 of the printing couple frame adjacent the pulley 207 is a lever 243, the upper end of which is pivotally attached to the rod 135 operated to release the spring pressure on the presser rolls of the printing couples. The lower end of the lever 243 is formed to provide a cam surface 245, which is effective to engage with and depress the roller 247, mounted on a laterally projecting pin 249 on the end of the arm 227, when the bar 135 is moved to the left, as viewed in Fig. 15, and thus throw out the clutch for the pulley 207. Thus when the bar 135 is moved to the left, as viewed in Fig. 1, to relieve the spring pressure on the presser rolls, which will stop the feeding of the strip, the clutch for the pulley 207 is thrown out, and the reel 7, which winds the strip, ceases to rotate. When the arm is moved to the right, to move the parts into their positions shown in the drawings, the presser rolls are yieldingly forced against the print rolls and the reel 13 is caused to rotate.

The strip 9, after it leaves the left hand printing couple of Fig. 1, passes through a drier to the right hand printing couple of that figure. It is then guided upward by suitable rollers to be again presented to the drier, and finally passes over a roll 251 and is led to the winding reel 13.

Heretofore considerable difficulty has been experienced in properly tensioning and guiding narrow strips to winding reels. This problem has been satisfactorily solved by the guide illustrated in Figs. 1, 6, and 7. As illustrated, this guide comprises a bar 253 having a laterally projecting, cylindrical pin 255 which is rotatably and adjustably received in a perforated boss 257 on the end of a supporting arm 259 carried by the bed of the machine. The set screw 260 serves to hold the pin 255 in its adjusted longitudinal and rotative positions. Laterally projecting from the bar 253 are a plurality of spaced cylindrical bars 261 which extend through perforations in a bar 283, this bar being adjustably slidable on the bars 261 and being secured in adjusted position by set screws 265. In operation the bars 263 are adjusted so that the sheet loosely fits between that bar and the bar 253. As best shown by Fig. 7, the bars 261 are so positioned that the sheet contacts with those bars through a small arc, so as to exert friction on the sheet, which is done by making the middle bar of each group of three adjacent bars offset toward the sheet with relation to the two side bars of that group.

As shown, the drier comprises a funnel 267 provided with an air heater 269, preferably of the electric type, through the interstices of which

the air entering the lower opening 271 controlled by the damper 273 is forced by the electric motor driven fan 275. The lower pass of the strip, as illustrated, passes through openings 277 in the 5 walls of the funnel. The top of the funnel is open so that heated air rising from the funnel dries the upper passes of the strip. The width of the funnel transversely of the sheet is slightly greater than the width of the sheet so as to permit 10 free passage of air past the lower pass of the strip, and the strip is so guided as to have its printed side lowermost.

For permitting ready removal of the presser roll shaft 101 from its supporting arms 103, conveniently the latter are formed with large openings 279 (Fig. 12) into which enter the reduced end portions 281 (Figs. 4 and 12) of the shaft. Preferably, the shaft is mounted on the arms 103 in ball-bearings 283, one of which is shown in 20 Fig. 12 as removed from the arm. As will be obvious, by moving the bearing to the left from its position shown in Fig. 12, the outer periphery of the bearing will be received in the opening 279, while the reduced end of the shaft will enter the 25 opening 285 of the bearing. When the bearing is thus inserted in the opening 279, it will abut with the shoulder 287 on the shaft, which will prevent it from moving farther toward the presser roll. For retaining the bearings in the openings 30 279, the arms 103 carry covers for the openings. As illustrated, these covers are in the form of flat plates 289 secured to the arms by removable screws 291. If desired, one or both of the covers may be notched as at 293 (Fig. 3) for receiving 35 the upper screw 291. This enables the cover to be swung downward, about the lower screw as a pivot, upon loosening the upper screw, into its position shown in Fig. 12, so as to expose the bearing and permit its removal from the arm 40 103.

As shown, the ink pan 295, into which the print roll dips, is carried on the end of a vertically positioned rod 297 (Fig. 4) slidably mounted in a perforation 298 formed in a horizontal bar 299, which bar is formed integrally with the side members 15 and 17 of the printing couple frame. Conveniently, the rod 297 is circular, and is prevented from rotating by a rod 300 secured to the pan and extending through and slidably fitting 45 a perforation in the bar 299. As shown, the rod 297 is formed on one side thereof with rack teeth 301 with which meshes a rack pinion 303, the latter being carried by a shaft 305 rotatably mounted at opposite end portions in the opposite 50 side members 15 and 17 of the frame. By rotating the shaft 305, by means of its handle knob 307 at the side of the frame, the ink pan may be raised and lowered. As shown, for holding the ink pan in adjusted positions, the shaft 305 has 55 fixed thereto a ratchet wheel 309 with which meshes a releasable pawl 311 (Fig. 3).

It will be understood that wide deviations may be made from the form of the invention herein described without departing from the spirit of 60 the invention.

I claim:

1. In a device of the character described, a print roll, a presser roll, a movable mounting for the latter for moving the presser roll into and 65 out of cooperation with the print roll, and a work guide carried by said mounting.

2. In a device of the character described, a print roll, a presser roll, a movable mounting for the latter for moving the presser roll into and 70 out of cooperation with the print roll, spring

means for moving said mounting to hold said presser roll resiliently in cooperation with said print roll, a releasable abutment for said spring means, and a work guide carried by said mounting.

3. In a device of the character described, a frame, a print roll removably mounted on said frame, a presser roll cooperating with said print roll, a mounting for said presser roll movably carried by said frame whereby the presser roll 10 may be moved away from said print roll to permit removal of the latter from the frame, and a work guide carried by said mounting.

4. In a device of the character described, a frame, a print roll removably mounted on said 15 frame, a presser roll cooperating with said print roll, a mounting for said presser roll movably carried by said frame whereby the presser roll may be moved away from said print roll to permit removal of the latter from the frame, spring 20 means acting on said mounting having a releasable abutment which when released is movable to permit such movement of said mounting, and a work guide carried by said mounting.

5. In a device of the character described, a 25 frame, a print roll carried by said frame, a presser roll cooperating with said print roll, bearings for said presser roll, a swinging support mounted on said frame and carrying said bearings, means urging said support to swing said 30 presser roll away from said print roll, and a releasable toggle mechanism operatively acting between said frame and swinging support for holding said presser roll in operative relation to said print roll.

6. In a device of the character described, a frame, a print roll carried by said frame, a presser roll cooperating with said print roll, bearings for said presser roll, a swinging support mounted on said frame and carrying said bearings, means urging said support to swing said 40 presser roll away from said print roll, a spring for holding said presser roll in operative relation to said print roll against the effort of said means, an abutment for said spring, and a releasable 45 toggle for said abutment.

7. In a device of the character described, a frame, a print roll carried by said frame, a presser roll cooperating with said print roll, bearings for said presser roll, a movable support 50 mounted on said frame and carrying said bearings, means urging said support to move said presser roll away from said print roll, and a releasable toggle mechanism operatively acting between said frame and movable support for holding said presser roll in operative relation to said print roll, said toggle mechanism when released permitting movement of said support a distance 55 at least the radius of said print roll.

8. In a device of the character described, a frame, bearings on said frame, a print roll mounted on said bearings, a presser roll cooperating with said print roll, a mounting carrying bearings for said presser roll, which mounting is movably mounted on said frame, a spring operatively acting on said mounting for holding said presser roll resiliently in cooperation with said print roll, and means forming a releasable abutment for said spring for permitting free movement of said mounting transversely of said 70 print roll a distance of at least the radius of said print roll to permit removal of the latter from its bearings by motion transversely thereof.

9. In a device of the character described, a print roll, a presser roll, a mounting carrying 75

bearings for said presser roll movable transversely of said print roll, a spring operatively acting on said mounting for holding said presser roll in resilient cooperation with said print roll, an abutment for said spring, and means forming a releasable toggle for supporting said abutment.

10. In a device of the character described, a print roll, a presser roll, a mounting carrying bearings for said presser roll movable transversely of said print roll, a spring operatively acting on said mounting for holding said presser roll in resilient cooperation with said print roll, means forming an abutment for said spring, and means 15 forming a toggle support for said abutment for transmitting the effort of said spring to said mounting.

11. In a printing press, a plurality of driven instrumentalities for operating upon a web, one 20 at least of which is a printing couple having a print roll and a presser roll between which the web passes and which feed the same, and another of which is driven by means including a clutch, spring means for yieldingly urging said 25 rolls into cooperation, and a single operator controlled means for rendering said spring means inoperative to interrupt feeding of the web and for throwing out said clutch for interrupting operation of the other instrumentality.

30. 12. In a printing press, a plurality of driven instrumentalities for operating upon a web, one at least of which is a printing couple having a print roll and a presser roll between which the web passes and which feed the same, and another of which is driven by means including a 35 clutch, a spring for yieldingly urging said rolls into cooperation, means for transmitting the effort of said spring comprising an abutment for said spring, a toggle supporting said abutment, and a single operator controlled means for breaking the toggle to interrupt feeding of the web and for throwing out said clutch for interrupting operation of the other instrumentality.

13. In a printing press, a printing couple comprising a print roll and a presser roll for operating upon a web and for feeding the same, spring means for urging said rolls resiliently into 45 cooperation, a reeling mechanism for the web, driving means for said couple and reeling mecha-

nism including a clutch for establishing and interrupting operation of the latter, and a single operator controlled means for rendering said spring means inoperative to interrupt feeding of the web and for throwing out said clutch for interrupting operation of said reeling mechanism. 5

14. In a printing press, a printing couple comprising a print roll and a presser roll for operating upon a web and for feeding the same, a spring for urging said presser roll toward said print roll, means for transmitting the effort of said spring to said presser roll comprising an abutment for said spring, a toggle supporting said abutment, a reeling mechanism for the web, means comprising a clutch for driving said reeling mechanism, and a single operator controlled means for breaking the toggle to interrupt feeding of the web and for throwing out said clutch for interrupting operation of said reeling mechanism. 10 15 20

15. In a printing press, a printing couple comprising a print roll and a presser roll for operating upon and feeding a web, means urging separation of said rolls, means for holding said rolls in cooperating relation against the effort of said means which urges them to separate, a reeling mechanism for the printed web, driving means for said reeling mechanism including a clutch, and a single operator controlled means for substantially simultaneously throwing out said clutch 25 30 for interrupting operation of said reeling mechanism and rendering inoperative said means which holds said rolls in cooperating relation for interrupting feeding of the web.

16. In a printing press, a printing couple comprising a print roll and a presser roll for operating upon and feeding the web, means urging separation of said rolls, means comprising a toggle for holding said rolls in cooperating relation against the effort of said means which urges them 40 to separate, a reeling mechanism for the printed web, driving means for said reeling mechanism including a clutch, and a single operator controlled means for substantially simultaneously throwing out said clutch for interrupting operation of said reeling mechanism and breaking said toggle for interrupting feeding of the web. 45
